UNITED STATES PATENT OFFICE.

W. P. CRAIG AND W. R. RIGHTOR, OF NEWPORT, KENTUCKY.

SIGNAL FOR VESSELS.

Specification of Letters Patent No. 14,226, dated February 12, 1856.

To all whom it may concern:

Be it known that we, WALDO P. CRAIG and WILLIAM R. RIGHTOR, both of Newport, in the county of Campbell and State of Kentucky, have invented a new and Improved Arrangement of Signal-Lights for Preventing Marine Collisions; and we do hereby declare the following to be a clear and exact description thereof, reference being had 10 to the accompanying drawings, making part of this specification.

The object of our invention is to afford to vessels approaching each other in the night time or during a fog a prompt and unfailing 15 indication of each other's courses.

Our invention consists in an ascending range of light so placed in the longitudinal center of the boat or vessel, as to be conspicuously visible viewed from another vessel toward which the first is heading, the foremost light being placed the lowest and the others in succession upward and astern of their predecessors, &c., that if one vessel is steering directly toward another, it will 20 be made manifest by the lights appearing in a vertical line one above the other. The slightest change of course is manifested by the direction of the sloping range of lights the foremost being the lowest. For a steam- 25 boat for example our range lights may be three in number to be placed in the longitudinal center of the boat. The first may be placed at her stern or if it should be preferred it might be say six to ten feet high 30 on the jack staff, the second, forward of pilot house at the verge of upper deck, to be higher (at all events) than the first, the third still further elevated to the top of pilot house, or suspended between the chim- 35 neys, (or in front of the chimney, where only one chimney is used.) The lights one above the other, and reaching back with their established relative position and angle 40 would unerringly show the heading or 45 course of the steamer; these lights may be screened behind so as not to interfere with the observations of the pilot.

In the accompanying drawings, Figure A is a plan representing two steamers heading

toward each other on a direct course. Fig. 50 B is a plan showing the courses of two opposing steamers in an elbow or bend of the river. Fig. C is a side elevation of a steam boat rigged with our signals.

In Fig. A Nos. 1, 2 and 3, are our range 55 lights on a descending steamer, while Nos. 4, 5, and 6 are our range lights on an ascending steamer. As the lights are in range it will be observed the vessels are approaching each other on a direct line and that unless the course of one or both is changed, a collision must ensue. A slight veering of either, at once disturbs the range of lights and will present an angle immediately observable to either pilot. Example Nos. 7, 8, 65 60 and 9, and 10, 11, and 12, show that by the time the vessels would have met, they are at a and a' respectively and out of all danger.

Again, suppose d , the track of an ascending steamer turning an abrupt point or 70 headland, while a descending steamer is about to cross her track in the channel. At this moment their relative positions appear critical; but the angular position of the range lights on the descending steamer, at 75 once indicates her heading to the pilot of the ascending one, who at once knows his duty, and without hesitation turns his boat on the line e thereby escaping all danger.

(c) is the line of observation. 80

We claim as new and of our invention—

A range of lights placed in the forward part and in the longitudinal center of a vessel the foremost light being the lowest and the following ones rising in succession above 85 it; so as to present to an observer in or near the line of its course a range of light which is either vertical or is directed obliquely to starboard or larboard according to the course of the vessel. 90

Witness our hands before two subscribing witnesses.

W. P. CRAIG.
WM. R. RIGHTOR.
